WILLIAM W. WILSON, OF LOS ANGELES, CALIFORNIA.

UNDERREAMER.

1,342,406.

Specification of Letters Patent. Patented June 1, 1920.

Application filed July 26, 1916. Serial No. 111,437.

To all whom it may concern:

Be it known that I, WILLIAM W. WILSON, a citizen of the United States, residing at Los Angeles, in the county of Los Angeles and State of California, have invented new and useful Improvements in Underreamers, of which the following is a specification.

This invention relates to underreamers for enlarging well holes, and particularly underreamers used in enlarging oil well holes so that the tubing or casing lowered in the holes as the drilling or hole production advances may be lowered, such underreamers serving in operation to reduce, remove or break down the shell or shoulder left beneath the casing in the operation of the drilling string which ordinarily only cuts the hole to a diameter equivalent to the inner diameter of the casing. Letters Patent on various types of underreamers have been previously issued, such as that covered by Letters Patent No. 827,595, issued to E. C. Wilson July 31, 1906. These underreamers have been extensively manufactured and to a large extent have taken the field in California and in foreign countries. In my association with the exploitation of such underreamer, and in my extensive examination of the prior art, I have hit upon various combinations and inter-relations of reamer parts and features, one such entity, which I believe to satisfy the desiderata necessarily entering into underreamer practice, constitutes the present invention. The invention has for its object the provision of an improved underreamer, being a radical departure from the prior art in combination and inter-relation and coöperation of parts and features and which will be superior in point of relative simplicity and inexpensiveness of construction, taken in connection with durability, positiveness of operation, reliability in service, facility in assembling and dismantling or disconnection of parts, and facility and convenience in repair or replacement or resharpening or remachining of parts and features, including such facility in such treatment as will extend the length of life of the same without replacement of parts or members, and which will be generally superior in point of reaming efficiency and general serviceability.

With the above and other objects in view, the invention consists in the novel and useful provision, formation, combination, association, inter-relation and coöperation of

parts, members and features, all as herein-after described, shown in the drawing, and finally pointed out in claims.

In an accompanying application filed July 26, 1916, Serial Number 111,438, I have disclosed and described and separately claimed the article of manufacture constituting the body portion of the improved underreamer disclosed, described and claimed herein, and thus in said other application considered irrespective of the inter-relation and coöperation of such body with the other features of the reamer, as herein disclosed, described and claimed.

In the drawing:

Figure 1 is a central longitudinal sectional view, partly broken away and partly in elevation, of an underreamer constructed and organized in accordance with the invention, the bits or cutters being shown in expanded or working positions;

Fig. 2 is a view similar to Fig. 1, the bits or cutters being shown in collapsed or inoperative positions;

Fig. 3 is a fragmentary view, in elevation, of the lower portion of the reamer-body construction shown in Figs. 1 and 2, in elevation, the cutters being indicated in dotted lines;

Fig. 4 is a view similar to Fig. 3, and taken at right angles thereto;

Fig. 5 is a bottom end or plan view of the underreamer body shown in the other figures;

Fig. 6 is a detail transverse sectional view, taken upon the line x^6-x^6 , Fig. 1, and looking upwardly; and

Fig. 7 is a detail inner face view of one of the cutters or bits of the improved underreamer in detached position.

Corresponding parts in all the figures are designated by the same reference characters.

Referring with particularity to the drawing, the improved underreamer is shown as comprising an elongated body a , hollow in part or provided with a longitudinal chamber or bore 9 , produced in the same upwardly from the open bottom or mouth b , which latter comprises a substantially cylindrical upper portion 10 and diametrically opposed lugs or heads 11 which range downwardly from the bottom terminal portion of the cylindrical portion 10 . This latter portion provides in effect an internal flattened cylindrical chamber 10^a , which

- communicates with the bore 9, the latter being of less diameter than the chamber 10^a, so that a two-part shoulder 10^b is provided at the upper extremity of such chamber 10^a.
- 5 Cutters or bits B and C coöperate with the inner walls of the mouth portion 10, and with the lugs 11. These cutters are provided with elongated shank portions 12 preferably increasing in thickness at their opposed faces toward their median portions as at 12^a, and of proper width to be accommodated transversely of the chamber 10^a in opposed relation; and being further provided with rounded outer faces 12^b formed to fit and be engaged with the inner wall of the mouth portion 10 within the chamber 10^a and at the ends of such chamber as distinguished from the flattened side walls and chamber. Such cutters further comprise each a body 13 beneath the shank 12, which same is provided with lateral shoulders 13^a and 13^b respectively, each of said shoulders having a bearing face, 13^c and 13^d respectively, which bearing faces are adapted to coöperate with 20 and bear upon the lugs 11, upon upper spreading bearings 11^a, such shoulders being likewise adapted at their upper inner edges 13^e to co-act and coöperate with lower spreading bearings 11^b upon such lugs 11.
- 25 Each of such lugs is provided with two of such upper spreading bearings 11^a and with two of such lower spreading bearings 11^b, and the bearing faces 13^c and 13^d are adapted to traverse the upper spreading bearings 30 11^a in the final portion of the action incident to expanding the cutters, and likewise in the initial portion of the action incident to collapsing such cutters; while the upper edge portions 13^e of the shoulders 13^a and 13^b 35 engage with the lower spreading bearings 11^b in the final stages of the collapsing action and the initial stages of the expanding action of the cutters. D designates operating means for the cutters, being in the 40 main mounted and confined within the bore or chamber 9 in the body a, and same is shown as comprising a rod or stem 14 operatively connected at its lower end 15 with the shanks 12 of the cutters, as by means of 45 50 a T formation comprising members 15^a taking into the eyes or recesses 15^b in the inner faces of the shanks at the upper ends thereof, such shanks being slightly beveled at their upper ends, from the tops thereof 55 downwardly into the outer faces 12^b thereof, as at 12^c, so as to permit the initiation of the collapsing and the termination of the expanding action so as to accommodate the cutters. The rod 14 is spring-actuated, being surrounded by coil spring 16, such coil spring, or a washer 17 resting upon the same at its upper end, bearing against a cotter pin or the like 18, detachably seated in the upper end of the rod 15. The lower end of 60 65 the coil spring 16 is confined by a removable stop c, which in accordance with Letters Patent previously issued to E. C. Wilson for underreamer, No. 1,183,151, dated May 16, 1916, may comprise a key consisting of an elongated flat body 19 provided at its lower edge with a depending wing or extension 20 fitting downwardly into the bore 9 of the body a, and passed into position within a transverse slot 21 formed in the reamer body a above the two-part shoulder 70 75 10^b, and likewise passed through an elongated slot 22 in the rod 14; the slot 21 being slightly enlarged vertically so as to permit the wing 20 to be passed into position as stated, and displaced therefrom, the upper corners of such key body likewise being beveled off as at 23 to permit ready insertion or removal.
- The upper end of the body a may be provided with the usual threaded tapered joint 80 member or pin 24 adapted to be received in a complementary threaded joint member, not shown, upon the string of tools, or carried by a cable, by which the underreamer is vertically reciprocated in the hole in the 85 reaming operation.
- The operation, method of use, mode of assemblage and dismantling, and mode of operation, of an improved underreamer embodying the invention, will be readily understood from the foregoing description taken in connection with the accompanying drawing and the following statement, all as exemplified by the particular embodiment 90 of the invention therein disclosed.
- The cutters B and C are mounted upon the T head 15, and the rod 14 with its surrounding spring 16 and washer 17 and cotter pin 18 is passed upwardly into the bore or chamber 9 through the open mouth b at 100 the lower end of the reamer-body. A suitable pilot key or wedge or other device is employed to pry up the lower end of the spring 16, and the detachable spring stop or key c is entered in the transverse slot 21 and driven under the spring until the wing or extension 20 rides into the bore 9, whereupon such key will be held in place by the compression of the spring coöperating with the action of the extension 20 to prevent 105 movement of the key in either lengthwise direction. The cutters now raised at their bearing faces 13^a and 13^b upon the upper spreading bearings 11^a, the upper ends of the shanks 12 bearing against the two-part shoulder 10^b at the upper end of the chamber 10^a. The cutters are thus in expanded condition or positions, and so held by the action of the spring 16. In order to dismantle the reamer, a suitable wedge is applied beneath one end of the key c, raising the key in the slots 22 and 21, so that the wing 20 comes above the lower wall of the slot 21, whereupon a suitable implement 110 115 120 125 130 may be used to drive the key endwise from

its position in said slots and free of the reamer body *a*, whereupon the rod 14 and its spring and connected parts may be drawn downwardly and the cutter shanks with 5 drawn from the mouth *b* and disconnected from the T head 15 for purposes of sharpening, dressing, or replacement. The detachable stop means or key *c* thus serves as means for operatively connecting the cutters and the spring-actuated rod 14 with the body *a*.

When the reamer is to be introduced within the well hole, for use, the cutters B and C are brought together or collapsed by holding reamer-body *a* and drawing downwardly upon the cutters, until the shoulder edges 13^a ride down upon the lower spreading bearings 13^b, as shown in Fig. 2, the spring 16 being thus put under compression. 10 The cutters in this performance teeter upon the T head 15, the cutter bodies 13 approaching each other beneath the lugs 11 and moving into a compass sufficiently small so that the reamer-body with such cutters may be introduced within the casing or tubing in 15 the wall and lowered therein until the cutters reach a point beneath the lower end of or shoe upon the casing, which is indicated fragmentarily at *d* in Fig. 1. Thereupon, 20 the cutters are permitted to ride outwardly and upwardly at their shoulders upon the lower spreading bearings 11^b, and to ride outwardly and upwardly at said shoulders upon the upper spreading bearings 11^a, under 25 the urge of the compressed spring 16, which tends to elevate the rod 14 and such cutters, the cutters finally assuming the positions shown in Fig. 1. The reamer cutters are then in position beneath the casing, 30 which is raised somewhat above the shoulder or shell in the walls of the hole to be reamed, to the end that the cutters may have a zone in which to commence to operate. Part of the cutter intrust is taken by the 35 T head 15, part likewise being taken by the upper spreading bearings 11^a. Out-thrust of the cutters is taken by the outer walls of the chamber 10^a, and up-thrust is taken by the two-part shoulder 10^b. The reamer is 40 now operated in the usual manner by reciprocating it vertically by means of the string or cable operated above the mouth of the hole by a walking beam or the like. When it is desired to discontinue the reaming 45 operation and remove the reamer from the hole, the reamer is drawn upwardly by the string or cable, until the bodies 13 of the cutters, at their outwardly projected top portions 13^c engage with the lower end of 50 the shoe or the casing *d*, whereupon continued elevation of the reamer body will be accompanied by temporary arrest of the upward movement of the spring-actuated rod and connected parts of the cutters, which 55 will travel at the shoulders of the cutters

downwardly and inwardly across the upper and lower spreading bearings 11^a and 11^b, until the cutters come into the collapsed position as shown in Fig. 2, whereupon the cutters likewise, with the spring-actuated 70 rod and connected parts, will be drawn upwardly through the casing with the reamer-body *a*, and may be removed from the upper end of the casing at the mouth of the hole.

In the expanding action of the cutters the rounded outer faces 12^b of the shanks of the cutters effectually coöperate with the inner curved walls of the cylindrical mouth portion 10, or the outer curved walls of the chamber 10^a, producing a rocking or teetering motion of the cutters upon the T head 15 in contradistinction from the sliding action which tends to weaken the cutters and cause breakage. The cutter shanks are permitted to be formed of extreme thickness, inasmuch as they do not have to ride over any intermediate spreading portion or partition or wedge between such shanks. Furthermore, the shanks are entirely enclosed within the cylindrical mouth portion 10, which latter is devoid of any openings through which said cutter shanks might project, in accordance with certain previous practice. The cutters and such mouth *d* are 85 likewise devoid of any of the shoulders, ways or dovetails which heretofore have been extensively employed in underreamers, for inter-relating the cutter shanks and the body of the reamer, and which dovetails, ways, etc., are liable to fracture, as particularly in the so-called "Double" underreamer in which latter reamer likewise the objectionable tilting and sliding action of the shanks upon the means for connection with the 90 spring-actuated rod is found in practice, and in which likewise an objectionable interposed wedge or partition or extension between the cutter shanks is found. In the present reamer, in contradistinction from 95 such "Double" reamer, and in common with the reamer of prior Letters Patent issued to E. C. Wilson, the mouth *b* of the reamer-body may be machined or cut back, up into the stock of the body, so as to renew the 100 body in case of wear following long service, or in case of injury, it being understood that these devices are subjected to heavy service and are frequently employed beneath a heavy string of tools thousands of feet beneath the surface of the earth. Such machining is likewise not possible with the so-called "Double" underreamer, and in referring to such "Double" underreamer reference is made more particularly to the underreamer of the patent issued to Edward Double July 28, 1903, for Underreamer, No. 734,833. In so re-machining the mouth of the present reamer, the two-part shoulder 10^b is cut back, as are the lugs 11 and the 110 115 120 125 130

lower edge of the mouth portion 10, and, if desired, the transverse slot 21 in the body may be plugged up and a new transverse slot produced above it for the key or spring-
 5 holding stop *c*. The cutters of the present underreamer are exceptionally strong, overcoming the many objections attaching to the cutters of the said "Double" reamer, which have inwardly directed shoulders formed by
 10 producing recesses in the inner faces of the shanks of the cutters which materially and often fatally weaken such cutter shanks. If a breakage of such cutters occurs in the use of the reamer the cutter parts frequently
 15 drop into the hole and require expensive and annoying "fishing" operations to remove them, or even at times drilling out such broken cutter parts or abandoning of the well hole.
 20 I am not aware that any such combination and inter-relations of reamer-mouth-construction including the continuous walled-chamber and the lugs 11 depending therefrom, together with the cutter bodies
 25 and shanks as constructed and as coöperating with such reamer-mouth-formation, has ever been devised prior to my invention thereof, and the same provides many features and factors of advantage in superi-
 30 ority, all as hereinabove set forth.

It is manifest that many advantages may be made with relation to construction, formation, and details thereof, all with relation to the construction and organization
 35 herein described and disclosed in the drawing, without departing from the true spirit of the invention and a fair interpretation thereof.

Having thus disclosed my invention, I
 40 claim and desire to secure by Letters Patent:

1. An underreamer comprising a body with a chamber in its lower end, which chamber is laterally closed around its periphery and opens downwardly at the lower
 45 end of the body, a pair of spreading lugs projecting downwardly from the body end at opposite sides of the chamber and each having upwardly diverging wedge faces, the chamber and the lower opening of the
 50 chamber being free and unobstructed for sole occupancy by cutters, oppositely disposed cutters having shanks extending up into the chamber, said cutters each having laterally extending shoulders to engage the
 55 wedge faces of the opposite spreading lugs, and cutter supporting and actuating means to which the cutters are pivotally attached at the upper ends of their shanks.

2. An underreamer comprising a body
 60 with a chamber in its lower end, which chamber is laterally closed around its periphery and opens downwardly at the lower end of the body, a pair of spreading lugs projecting downwardly from the body end
 65 at opposite sides of the chamber and each

having upwardly diverging wedge faces, the chamber and the lower opening of the chamber being free and unobstructed for sole occupancy by cutters, oppositely disposed cutters having shanks extending up
 70 into the chamber, said cutters each having laterally extending shoulders to engage the wedge faces of the opposite spreading lugs, said shoulders being located on the cutters in positions outwardly removed from the
 75 inner opposing faces of the cutters and the cutters extending inwardly past said shoulders and between the opposite spreading lugs, and cutter supporting and actuating means to which the cutters are pivotally
 80 attached at the upper ends of their shanks.

3. An underreamer comprising a body with a chamber in its lower end, which chamber is laterally closed around its periphery and opens downwardly at the lower
 85 end of the body, a pair of spreading lugs projecting downwardly from the body end at opposite sides of the chamber and each having upwardly diverging wedge faces, the chamber and the lower opening of the
 90 chamber being free and unobstructed for sole occupancy by cutters, oppositely disposed cutters having shanks extending up into the chamber, said cutters each having laterally extending shoulders to engage the
 95 wedge faces of the opposite spreading lugs, said diverging wedge faces of the spreading lugs being situated on opposite sides of a vertical plane central of the body and the cutters being located symmetrically with
 100 respect to said plane; and cutter supporting and actuating means to which the cutters are pivotally attached at the upper ends of their shanks so that the cutters swing on pivotal points located as near to their outer
 105 surfaces as to said central plane.

4. An underreamer comprising a body with a chamber in its lower end, which chamber is laterally closed around its periphery and opens downwardly at the lower
 110 end of the body, a pair of spreading lugs projecting downwardly from the body end at opposite sides of the chamber and each having upwardly diverging wedge faces, the chamber and the lower opening of the
 115 chamber being free and unobstructed for sole occupancy by cutters, oppositely disposed cutters having shanks extending up into the chamber, said cutters each having laterally extending shoulders to engage the
 120 wedge faces of the opposite spreading lugs, and cutter supporting and actuating means to which the cutters are pivotally attached at the upper ends to their shanks; each spreading lug having a lower pair of up-
 125 wardly diverging wedge faces making a comparatively obtuse angle with each other and an upper pair of diverging wedge faces making a comparatively acute angle with each other, and the cutters being forced
 130

- outwardly by upward travel over the last mentioned faces to a position where the outer surfaces of their shanks are forced against the walls of the chamber. 55
- 5 5. An underreamer comprising a body with a chamber in its lower end, which chamber is laterally closed around its periphery and opens downwardly at the lower end of the body, a pair of spreading lugs 60
- 10 projecting downwardly from the body end at opposite sides of the chamber and each having upwardly diverging wedge faces, the chamber and the lower opening of the chamber being free and unobstructed for 65
- 15 sole occupancy by cutters, oppositely disposed cutters having shanks extending up into the chamber, said cutters each having laterally extending shoulders to engage the wedge faces of the opposite spreading lugs, 70
- 20 said shoulders being located on the cutters in positions outwardly removed from the inner opposing faces of the cutters and the cutters extending inwardly past said shoulders and between the opposite spreading lugs, 75
- 25 said diverging wedge faces of the spreading lugs being situated on opposite sides of a vertical plane central of the body and the cutters being located symmetrically with respect to said plane; and cutter sup- 80
- 30 porting and actuating means to which the cutters are pivotally attached at the upper ends of their shanks so that the cutters swing on pivotal points located as near to their outer surfaces as to said central plane. 85
- 35 6. An underreamer comprising a body with a chamber in its lower end, which chamber is laterally closed around its periphery and opens downwardly at the lower end of the body, a pair of spreading lugs 90
- 40 projecting downwardly from the body end at opposite sides of the chamber and each having upwardly diverging wedge faces, the chamber and the lower opening of the chamber being free and unobstructed 95
- 45 for sole occupancy by cutters, oppositely disposed cutters having shanks extending up into the chamber, said cutters each having laterally extending shoulders to engage the wedge faces of the opposite spreading lugs, 100
- 50 said shoulders being located on the cutters in positions outwardly removed from the inner opposing faces of the cutters and the cutters extending inwardly past said shoulders and between the opposite spreading
- lugs, and cutter supporting and actuating means to which the cutters are pivotally attached at the upper ends to their shanks; each spreading lug having a lower pair of upwardly diverging wedge faces making a comparatively obtuse angle with each other and an upper pair of diverging wedge faces making a comparatively acute angle with each other, and the cutters being forced outwardly by upward travel over the last mentioned faces to a position where the outer surfaces of their shanks are forced against the walls of the chamber. 55
- 5 7. An underreamer comprising a body with a chamber in its lower end, which chamber is laterally closed around its periphery and opens downwardly at the lower end of the body, a pair of spreading lugs projecting downwardly from the body end at opposite sides of the chamber and each having upwardly diverging wedge faces, the chamber and the lower opening of the chamber being free and unobstructed for sole occupancy by cutters, oppositely disposed cutters having shanks extending up into the chamber, said cutters each having laterally extending shoulders to engage the wedge faces of the opposite spreading lugs, 70
- 20 said shoulders being located on the cutters in positions outwardly removed from the inner opposing faces of the cutters and the cutters extending inwardly past said shoulders and between the opposite spreading lugs, 75
- 25 said diverging wedge faces of the spreading lugs being situated on opposite sides of a vertical plane central of the body and the cutters being located symmetrically with respect to said plane; and cutter sup- 80
- 30 porting and actuating means to which the cutters are pivotally attached at the upper ends of their shanks so that the cutters swing on pivotal points located as near to their outer surfaces as to said central plane. 85
- 35 8. An underreamer comprising a body with a chamber in its lower end, which chamber is laterally closed around its periphery and opens downwardly at the lower end of the body, a pair of spreading lugs 90
- 40 projecting downwardly from the body end at opposite sides of the chamber and each having upwardly diverging wedge faces, the chamber and the lower opening of the chamber being free and unobstructed 95
- 45 for sole occupancy by cutters, oppositely disposed cutters having shanks extending up into the chamber, said cutters each having laterally extending shoulders to engage the wedge faces of the opposite spreading lugs, 100
- 50 said shoulders being located on the cutters in positions outwardly removed from the inner opposing faces of the cutters and the cutters extending inwardly past said shoulders and between the opposite spreading
